BENCH OR SIMILAR ARTICLE OF FURNITURE

John O. Van Koert, New York, N. Y., assignor to Drexel
Furniture Company, Drexel, N. C., a corporation of Delaware

Application August 2, 1955, Serial No. 37,265

Term of patent 7 years

(Cl. D15—8)

Fig. 1.

Fig. 2.

Figure 1 is a perspective view of a bench or similar article of furniture showing my new design; and

I claim:

The ornamental design for a bench or similar article of furniture, as shown.
